METHOD OF AND APPARATUS FOR PRODUC-
ING ARTIFICIAL SAUSAGE SKINSJulius Wolff, Amstenrade, Netherlands; vested in
the Attorney General of the United StatesApplication December 2, 1941, Serial No. 421,396
In Germany January 10, 1939

7 Claims. (Cl. 117—94)

1.

The present invention relates to a method of and an apparatus for producing artificial sausage skins.

In the manufacture of artificial sausage skins it is known to impregnate the outer or inner wall or surface of tubular fabrics with a suitable fibrous mass consisting of animal substances such as meat masses or meat fibres. For this purpose, the tubular fabric is drawn upwardly through an annular gap and hereby the impregnating mass is applied within or without to the tubular fabric.

According to the method of the present invention an impregnating mass is applied to the tubular fabric simultaneously without and within so that the outer as well as the inner surface of the finished tubular fabric is coated with an impregnating layer. In connection with such an impregnation it is of particular advantage to so carry out the coating of both faces of the fabric sleeve with the fibrous material, that the fibres at both sides or surfaces of the wall of the fabric sleeve cross each other. Hereby a special reinforcement of the impregnation and therewith a greater strength and durability of the artificial sausage skin is obtained. This is of particular importance if the tubular fabric is made of artificial silk which is not as strong as natural silk and, moreover, is more sensitive to moisture. Owing to the arrangement of the fibres in directions crossing each other upon the inner wall and the outer wall of the artificial sausage skin, the lower strength of the finished tubular sausage skin made of artificial silk is compensated by the reinforcement of the impregnation and, moreover, the sensitivity of the artificial silk to moisture is rendered ineffective by the fact that the tubular fabric is completely embedded in the fibrous mass.

The arrangement of the fibres of the two impregnating layers in directions crossing each other at the inner and outer surface of the artificial sausage skin is obtained in accordance with the invention by the fact that the inner and outer wiper members for the impregnating mass are rotated relatively to each other, while the tubular fabric is longitudinally drawn along these members. Hereby the fibres present in the impregnating mass are adjusted in the direction in which the wiper members move along the wall of the tubular fabric. If the wiper members are uniformly rotated about the axis of the moved tubular fabric, the fibres are helically directed, but if the inner wiper members rotate in a direction opposite to that of the outer member, the

2.

fibres are arranged in directions crossing each other, the angular position of the fibres relatively to each other corresponding to the speed of movement of the tubular fabric as well as of the wiper-members. Depending on the speed selected, the fibres may be arranged in a more flat or steep direction, and, moreover, the angular position upon the inner or outer side or surface may be differently chosen, if the wiper-members are rotated with different speeds also.

For carrying out the method according to the present invention preferably an apparatus is used as is shown by way of example in the accompanying drawing.

15. In this drawing:

Fig. 1 is a vertical section of the general arrangement of an impregnating apparatus without showing details of the apparatus, and

Fig. 2 shows a broken away section through the same apparatus on a larger scale, more particularly illustrating the special devices for carrying out the new method arranged at the upper and lower part of the apparatus.

Mounted upon a lower trough *a*, serving to receive impregnating mass eventually flowing off, is a frame *b* the upper end of which carries a trough *d* at about the height of a table above the floor *c* of the work room. In the bottom of the trough *d* any desired number of impregnating devices, depending on the selected number of tubular fabrics to be treated, is arranged side by side in one row. In the drawing, showing a cross section through the trough, the other devices are arranged behind the device illustrated, so that they are invisible. In the bottom of the trough *d* holes are provided into which the individual impregnating devices may be inserted. For this purpose each device is provided with a cylindrical bushing *e* having an upper supporting flange *f*.

40. In the middle axis of the bushing *e* a vertical pipe *g* is arranged which is fixed in the bottom of the lower trough *a* and extended through this bottom downwardly, where a horizontal pipe *h* is connected, introducing the impregnating mass 45 into the interior of the pipe *g* to flow upwardly therein and to be discharged through openings *i*, provided in the wall of the pipe *g* above the flange *f* of the bushing *e*, into the space between the pipe *g* and the tubular fabric *k* to be impregnated.

Any desired length of tubular fabric *k* is pushed upon a pipe *l* which in turn is pushed over the stand pipe *g* and extends to the bottom of the trough *a*. The upper end of the tubular fabric *k* is withdrawn from the supporting pipe *l* and

pulled upwardly through the bushing *e*. Within the latter a distance member *m* having a convex surface is mounted upon the pipe *g*. The outer diameter of the distance member *m* is somewhat smaller than the inner diameter of the bushing *e*, so that an annular gap is formed through which the tubular fabric may be drawn.

Within the pipe *g* a long spindle *n* is rotatably mounted the diameter of which from below the supply pipe *h* until above the discharge openings *i* is substantially smaller than the inner diameter of the pipe *g*, so that the impregnating mass may unimpededly be fed upwardly in the pipe *g*. Both ends of the spindle *n* are enlarged to the inner diameter of the pipe *g* so that above and below the mass cannot be discharged. To this purpose, moreover, special sealing means may be provided at the ends of the pipe *g*. The lower end of the spindle is extended through the pipe *g* and carries a worm wheel *o* which by means of a cylindrical projection or rim *p* is journaled in a ball bearing *q*. The drive of the worm wheel *o* is effected by the worm *r* the shaft *s* of which simultaneously drives the worms and worm wheels of the other devices. The drive may be effected by an electromotor.

The upper end of the spindle *n* also extends through the pipe *g* and is provided with a square *t* upon which may be mounted two supporting bodies *u* for the inner wiper members *v*. The latter consist of circular discs the edges of which are rounded off. These discs are rotated by way of the supporting bodies *u* by means of the spindle *n*. At the outer side or surface of the tubular fabric *k* another wiper ring *w* is arranged in a level between the two inner wiper members *v*. The wiper ring *w* is fixed to a worm wheel *x* rotated by a worm *y* the shaft *z* of which simultaneously drives the worms of the other devices in the same manner as the lower shaft *s* drives the worms as described above. The worm wheel *x* runs on a ball bearing which is supported by way of the bolts or studs *z'* from the flange *f* of the bushing *e*.

If the worm wheels *o* and *x* are rotated in opposite directions, the inner and outer wiper members *v* and *w* respectively rotate correspondingly and thereby also correspondingly apply the fibres of the impregnating mass to the tubular fabric *k*, so that the fibres upon the inner and outer side respectively cross each other. Details of the device may, of course, be modified without departing from the spirit of the invention.

What I claim is:

1. That method of coating tubular fabrics with a fibrous mass of impregnating material, the steps of which comprise applying said mass to the outer and inner surfaces of a tubular fabric, and then advancing said tubular fabric along the longitudinal axis thereof while wiping the fibres in the applied mass on said inner and outer surfaces respectively at intersecting angles.

2. That method of coating tubular fabrics with a fibrous mass of impregnating material, the steps of which comprise applying said mass to the outer and inner surfaces of a tubular fabric, and then advancing said tubular fabric along the longitudinal axis thereof while wiping the fibres in the applied mass on said inner and outer tubular surfaces respectively in opposite circumferential directions.

3. That method of coating tubular fabrics with a fibrous mass of impregnating material, the steps of which comprise applying said mass to the outer and inner surfaces of a tubular fabric,

and then advancing said tubular fabric along the longitudinal axis thereof while wiping the fibres in the applied mass on the respective inner and outer surfaces circumferentially at different rates 5 whereby the fibres on one of said surfaces will be positioned at an intersecting angle with the fibres on the other surface.

4. That method of coating tubular fabrics with a fibrous mass of impregnating material, the 10 steps of which comprise applying said mass to the outer and inner surfaces of a tubular fabric, and then wiping the fibres in the applied mass on said inner and outer tubular surfaces respectively along oppositely pitched helical paths.

15 5. A device for producing impregnated tubular sausage skins and the like, comprising means for supplying an impregnating mass to the outer surface of said tubular skin, an outer wiper member for wipingly contacting said outer surface and the applied mass, means for mounting said wiper 20 for rotation circumferentially about said tubular skin, means for supplying said mass to the inner surface of said tubular skin, an inner wiper member, means for mounting said inner wiper for circumferential rotation within the tubular skin 25 at a point substantially opposite said outer wiper member, said inner wiper member adapted to wipingly contact said inner surface and the applied mass, means for supporting said skin for movement along the longitudinal axis thereof, and means individual to said wipers for rotating the latter during the longitudinal movement of said skin.

30 6. A device for producing impregnated tubular 35 fabric sausage skins and the like, comprising means for supplying a fibrous impregnating mass to the inner and outer surfaces of said tubular skin, a pair of spaced inner wiper members, means for mounting said wiper members for circumferential rotation within the tubular skin to 40 wipingly contact said inner surface and the applied mass, an outer wiper member, means for rotatably mounting said outer wiper member intermediate said spaced members to wipingly contact the outer skin surface and applied mass, means for supporting said skin for movement along the longitudinal axis thereof, and means individual to said inner pair of wiper members and to said outer wiper member for rotating said 45 members circumferentially of said tubular skin during the longitudinal movement of said skin.

50 7. A device for producing impregnated tubular fabric sausage skins and the like with a fibrous impregnating mass, comprising a pipe over which 55 said tubular skin is adapted to be inserted, a rotatable shaft coaxially mounted within the pipe and projecting beyond the end of said pipe, the diameter of said shaft being substantially smaller than the inside diameter of said pipe whereby 60 an annular passageway is provided, means for supplying the impregnation mass to said passageway, means for directing said mass from said passageway onto the interior surface of said skin, a pair of wiper members mounted on the projecting end of said shaft and adapted to engage the inner surface of said tubular skin as the latter is removed from said pipe over the wiper member, means for rotating said shaft and associated wiper members, and an annular supporting ring positioned intermediate said spaced wiper members and contacting the exterior surface of said tubular skin.
